UNITED STATES PATENT OFFICE.

CHARLES J. HOLUB, OF COLUMBUS, OHIO, ASSIGNOR TO THE LAMNECK COMPANY, OF COLUMBUS, OHIO, A CORPORATION OF OHIO.

MEANS FOR UNITING PIPE-SECTIONS.

1,324,897.

Specification of Letters Patent. Patented Dec. 16, 1919.

Application filed June 22, 1917. Serial No. 176,285.

To all whom it may concern:

Be it known that I, CHARLES J. HOLUB, a citizen of the United States, residing at Columbus, in the county of Franklin and State 5 of Ohio, have invented certain new and useful Improvements in Means for Uniting Pipe-Sections, of which the following is a specification.

This invention relates to means for uniting pipe sections, particularly such sections as are made of light material used for flue pipes, air conduits, etc., in connection with heating plants. While my invention is not particularly limited to this field, it is particularly adaptable to the same.

The main object of my invention resides in forming the meeting ends of adjacent sections so that the two parts may be telescoped slightly one within the other and securely 20 locked in such position. This I accomplish preferably by a coöperating fluted hem arrangement on opposite ends of the pipe, which hems are turned in and out respectively on the two pipe ends, to be in such 25 position to engage each other.

The preferred embodiment of my invention is shown in the accompanying sheet of drawings, in which similar characters of reference designate corresponding parts, and in 30 which:

Figure 1 is a fragmentary view in perspective of what I have termed the large end of the pipe section,

Fig. 2 is a fragmentary perspective of 35 what I have termed the small end of the pipe section,

Fig. 3 is an enlarged fragmentary section showing two pipe ends locked together, and,

Figs. 4, 5 and 6 are fragmentary sectional 40 views illustrating the manner in which the small end of the pipe section is formed.

In the drawings, the two coöperating pipe sections shown, are designated by the reference numerals 1 and 2, these pipes being 45 preferably made of very light material and being formed ordinarily from a flat sheet whose two longitudinal edges each have been provided with a hem arranged to interlock after the manner shown at 3. This manner 50 of forming pipe sections is well known in the art and forms no portion of the present invention. However, I have provided a novel means for holding the sheets to cylindrical

form, which means take the form of a stamped out tongue 4 turned back upon the 55 interlocking hems, as shown particularly in Fig. 2. It will be understood that it is only necessary to so lock the small end of a pipe, since this small end fits within the large end of the next succeeding pipe and consequently 60 holds this large end expanded. The locking tongue 4 is also so disposed that it will lie beneath the end of the next succeeding pipe when the parts are assembled.

To securely hold the various pipe sections 65 together, I have provided the edge portion of the large end with a hem 5 which is shown as fluted, it being the turned in portion only which is fluted and the outer portion being plain. The small end is formed as shown 70 diagrammatically in Figs. 4, 5 and 6, the edge portion of this small end being initially stretched as is shown at 6, this small end then being turned over to form a hem as shown at 7 and this hem then fluted as is 75 shown at 8, whereby both the interior and the outside of the small end is fluted. It will be understood that this fluting and turning is accomplished while the metal forming the parts, is in the flat and consequently because 80 of the stretched edge 6, the outturned portion of the hem on the small end of the pipe will project laterally away from the side of the pipe section to some considerable extent. This then forms the means for coöperating 85 with the inturned hem 5 on the large end of adjacent section to form a lock and because of the fluted nature of these hems, the portions may be more securely fastened together and in addition, because of these 90 fluted hems, the parts are prevented from rotating relatively with respect to each other.

An inspection of Fig. 2 will show that the locking tongue 4 is also so disposed as to be covered by the large end of the section 1 95 when the parts are united. Each of the sections 1 and 2 is also provided with an ornamental bead 9, the bead 9 on the section 2 being for the purpose of forming a shoulder for preventing the adjacent section from telescoping too far upon the same. This same bead 9 on the large end of the adjacent section is merely provided to give symmetry of appearance, but it will be noted from Fig. 3, that the length of the two hems is such 100 that when they are in the coöperative posi-

tion shown, the shoulder formed by the bead 9 on the section 2, prevents the section 1 from telescoping upon the same.

From the foregoing description, it will be apparent that I have provided a means for joining pipe ends which will rigidly hold the parts in their assembled relation preventing relative circular movement as well as detachment of the parts without permanently securing the parts together. Also, the sections are held locked in their round form by means of the tongues 4 which, when the sections are assembled, are covered to prevent their accidental separation.

15. What I claim is:

1. The combination with a pair of pipe sections, of means for joining the same comprising an inturned fluted hem on one of said sections, the outside being plain, and an outturned hem on the other of said sections, both the hem and pipe being fluted, said last named section being adapted to be fitted within the other section.

2. The combination with a pair of pipe sections, of means for joining the same comprising an inturned fluted hem on one of said sections, and an outturned fluted hem on the other of said sections whose lower edge is

enlarged to lie away from the side of the section, said last named section being adapted to be fitted within the other section.

3. The combination with a pair of pipe sections, of means for joining the same comprising an inturned fluted hem on one of said sections, an outturned fluted hem on the other of said sections whose lower edge is enlarged to lie away from the side of the section, said last named section being adapted to be fitted within the other section, and a shoulder formed in said inner section against which the edge of the outer section abuts when the parts are locked together.

4. The method of joining pipe ends which consists in forming a fluted inturned hem on one of said sections, stretching the end edge of the other section and then forming an outturned fluted hem on said last named section and then placing the end of said last named section within the other.

In testimony whereof I affix my signature 50 in presence of two witnesses.

CHARLES J. HOLUB.
